UNITED STATES PATENT OFFICE.

GUSTAVE A. OVERSTROM, OF PASADENA, CALIFORNIA.

ORE-CONCENTRATING TABLE.

1,417,682.

Specification of Letters Patent. Patented May 30, 1922.

Application filed July 17, 1918. Serial No. 245,309.

To all whom it may concern:

Be it known that I, GUSTAVE A. OVERSTROM, a citizen of the United States, residing at Pasadena, county of Los Angeles, 5 State of California, have made a certain new and useful Invention in Ore-Concentrating Tables, of which the following is a specification.

This invention relates to ore concentrat- 10 ing tables.

The object of the invention is to provide an ore concentrating table of the vibratory type which is simple in construction and effi- 15 cient in operation.

15 A further object of the invention is to provide an ore concentrating table of more or less universal application capable of handling without alteration, except possibly in the riffling, various sizes of material even 20 down to the condition of slimes.

A further object of the invention is to pro- 25 vide a concentrating table of the type referred to which is practically noiseless in operation.

25 A further object is to provide a concentrat- ing table of the vibratory type wherein the vibrations are imparted in an arcuate or circular direction generally lengthwise of the table.

30 A further object is to provide an ore concentrator of the percussion type in which the material travels away from the point where the percussion bump is taken.

35 Other objects of the invention will appear more fully hereinafter.

The invention consists substantially in the construction, combination, location and relative arrangement of parts, all as will be 40 more fully hereinafter set forth as shown in the accompanying drawings, and finally pointed out in the appended claims.

Referring to the accompanying drawings and to the various views and reference signs appearing thereon:—

45 Fig. 1 is a view in top plan of a concentrat- ing table embodying the principles of my invention.

Fig. 2 is a view in longitudinal section on the line 2, 2, Fig. 1, looking in the direction 50 of the arrows.

Fig. 3 is a view in end elevation.

Fig. 4 is a view in section on the line 4, 4, Fig. 1, looking in the direction of the arrows.

55 Fig. 5 is a view in longitudinal section on the line 5, 5, Fig. 4, looking in the direc- tion of the arrows.

Fig. 6 is a view in top plan of the lower frame of the supporting framework.

Fig. 7 is a detail view in diagrammatic top plan illustrating the circular arc motion im- 60 parted to the table surface.

Fig. 8 is a broken view in top plan dia- gram illustrating the concentrating action.

Figs. 9 and 10 are detached detail views respectively in side end elevations of the 65 spring supports.

Fig. 11 is a diagram illustrating the arcuate motion imparted to the table.

Fig. 12 is a broken view in elevation illus- trating the manner of attaching the spring 70 supports.

Fig. 13 is a detached detail view of the un- balanced wheel for imparting the vibra- tory motion to the table.

Fig. 14 is a view in section on the line 75 14, 14, Fig. 13, looking in the direction of the arrows.

Fig. 15 is a broken detail view in trans- 80 verse section through the table surface and the riffles thereof.

The same part is designated by the same reference numeral wherever the same occurs throughout the several views.

In its general structure the ore concentrat- 85 ing table embodying the principles of my invention consists generally of a transversely inclined rifled table surface which is hinged along the tailings discharge edge thereof to a shaking frame structure and supported along its feed and wash water supply edge 90 for adjustment to vary the transverse inclina- tion thereof. The shaking frame is sup- ported upon a floor framework by means of flexible supporting legs rigidly secured to the floor frame and to the shaking frame but 95 so constructed and disposed as to impart to the table surface an arcuate motion in the general direction of length of the table and in a manner and for a purpose herein- after more fully set forth, the motion being given to the table through the action of an unbalanced pulley. The riffles on the table surface are arranged to extend substan- tially in the direction of the circular arc motion imparted to the table.

Referring more particularly to Fig. 6 the floor frame is of generally rectangular out- line and includes parallel side stringers 16, 17, spaced apart from each other by trans- versely disposed girts 18. The blocks 19 110 are mounted upon the outside surfaces of the stringers 16, 17, and are bolted and doweled

to said stringers. An inclined bumping brace 20 abuts at one end against and is bolted to the center spacing girt 18 of the floor frame. The other end of the bumping brace is supported upon and bolted to a corbel 21 which in turn is bolted in spacing relation to the side stringers 16, 17. The strains of the bumping brace are distributed to the concentrator discharge ends of the floor frame stringers through braces 22. These braces also serve to maintain the rectangular shape of the floor frame. At the head motion end of the floor frame a spring post 23 is hinged to the inside surface of one of the stringers, as stringer 17, and a rod 24 connects the upper end of the spring post with the corbel 21. Through the rod 24 the post 23 may be adjusted upon its hinge to vary the pressure exerted by the spring 53 against the shaking frame.

The shaking frame in the particular form shown is of light cross braced structure with longitudinally extending outside stringers 25 spaced apart by spreader girts 26 (see Fig. 5). The spreader girt 26 at the head motion end of the shaking frame bears against the ends of reinforcing pieces 27 which are bolted and doweled to the inside surfaces of the stringers 25 in order to secure an efficient backing for said girt. Leg receiving and clamping blocks 28, corresponding and similar to the blocks 19 of the floor frame, are bolted or otherwise suitably secured to the shaking frame stringers 25. The shaking frame, if desired, and as indicated, may be still further braced by diagonal struts 29. A shaft 30 is clamped at its ends in the stringers 25 at the head motion end of the shaking frame and extends transversely of said frame, said shaft moving with said frame in the shaking movements thereof. The shaking frame stringer 25 on the feed side of the table is longer than the stringer on the tailings discharge side, the excess length occurring at the concentrates end of the table. Upon this extension is mounted a bracket 31 (see Fig. 5) which carries the adjusting screw 32. This screw engages the wedge member 33 which is mounted upon the upper surface of the extended stringer 25 and is retained in place thereon by means of side cleats 34. The wedge member 33 is formed with a plurality of inclined or wedge surfaces 35. At the tailings discharge side of the shaking frame standards 36 are bolted to the stringer 25 on that side, and to these standards are hinged the deck beams 37 of the table. A transverse deck beam 37 of the table 38 rests at the feed side of the table upon an inclined or wedge portion 35 of wedge member 33 so that by suitably adjusting the screw 32 the angle of transverse inclination of the table 38 may be varied.

65 The shaking frame is supported upon and

carried by the floor frame through supporting legs indicated generally at 39 which are not only of special structure to render them flexible, but are also specially disposed and arranged in order to secure the circular arc motion of the table. In the particular form shown (see Figs. 9, 10 and 12) the flexible supporting legs 39 are made up of flat strips of suitable flexible material. In practice I have found selected hickory to be suitable for this purpose, but, of course, I do not desire to be limited or restricted in respect to the particular material employed. I have indicated in Figs. 10 and 12 a flexible leg structure consisting of two flat strips 40, 41 placed flatwise against each other, and reinforced at the lower ends thereof on the head motion side and up to approximately the midlength point thereof by extra strips or leaves of successively varying lengths as indicated at 42, and similarly reinforced at their upper ends on the concentrates side by extra or auxiliary leaves or strips also of successively varying lengths as indicated at 43. All of the leaves, strips or plates constituting a flexible leg structure are bound together by suitable clamps indicated at 44. These flexible legs 39 are clamped at their lower ends in the clamp blocks 19 on the sides of the floor frame stringers 16, 17, and at their upper ends in the clamp blocks 28 applied to the stringers 25 of the shaking frame, and said flexible legs are so disposed that their edges present in a direction generally transverse to the lengths of the floor and shaking frames, and their flat surfaces present generally in the direction of the lengths of said frames. However, instead of the edges of the flexible legs presenting squarely in lines transverse to the floor and shaking frames, said legs are so set that their planes instead of being parallel to each other and at right angles to the lengths of the frames, are inclined towards a vertical plane containing the axis of the head motion shaft 30. This inclination of the legs 39 is clearly indicated in Figs. 6 and 11 by the diagram lines 45, 46. In Fig. 11 the diagram line 47 indicates the vertical plane of the axis of shaft 30, and it will be seen that the vertical planes of the flat sides or surfaces of the flexible legs 39 are in planes which are slightly inclined to the plane 47, and so inclined with reference to the plane 47 as to converge at a point 48, which should be in practice approximately fifty feet away from the side of the table. I have found in practice that this arrangement and disposition of the flexible legs is important in securing the objects and purposes of my invention, and therefore such arrangement constitutes a valuable feature of my invention. With such arrangement under the influence of the head motion reciprocal movements are imparted to the table in a direction generally

longitudinal of the table and practically parallel to the tailings discharge side at the head motion end of the table and which curve away from the tailings discharge side of the 5 table to a gradually increasing extent towards the concentrate discharge end of the table as indicated in Figs. 1, 7, 8 and 11, by the diagram lines 48.

From this description it will be seen that 10 the movements imparted to the table are substantially parallel with or in the direction of the length of the table at the feed end thereof and hence at substantially right angles to the flow of feed water in the 15 region of the table surface where the feed is supplied, where it settles, and where it initially stratifies. Towards the concentrates discharge end of the table, however, the reciprocatory movements imparted to the table 20 by the head motion depart from parallel relation to the table length and become more and more transverse thereto and at a decreasing inclination to the direction of transverse flow of the water across the table in the 25 region of the table surface where, after the pulp settles and stratifies, the values are separated therefrom. The table thus, in its reciprocatory movements, moves in a circular arc, the arc of movement having its 30 center lying a substantial distance away from the feed side or edge of the table and substantially in the vertical plane of the head motion end of the table, as above described. This peculiar motion imparted to 35 the table I call an arcuate or circular motion.

By the construction, mounting, clamping, and disposition of the flexible legs as above explained the bending strains imposed thereon during the shaking movements of the table are uniformly distributed, and consequently the flexible legs with reasonable care are practically indestructible. In practice, and in order to insure durability of the flexible legs, I prefer after the leaves or strips are assembled, to soak the legs for a considerable period of time, say, for a week or ten days, in crude oil or pine tar.

In addition to the slightly angular 50 position of the planes of the flat sides or faces of the flexible legs, as above explained, I also prefer to slightly incline the legs vertically and towards the head motion end of the table as clearly indicated in Figs. 2, 5 55 and 12. By reason of such vertical inclination away from the concentrates discharge end of the table a slight vertical movement is imparted to the table during its shaking movements which I have found in practice 60 to be beneficial in efficiently settling the mineral particles out of the mass of ores under treatment, and in advancing such particles towards the concentrates discharge end of the table.

55 Another and a most important and valuable result attained by the vertical inclination of the flexible legs will be comprehended when it is remembered that the head motion is not connected rigidly to a stationary part but the head motion shaft 30 is carried by and moves with the shaking frame. Consequently, the legs being slightly inclined vertically and towards the head motion end of the table, if the table carries a light load of ores to be treated the flexible 70 legs will bend less towards the head motion end than if the table were heavily loaded. Conversely, if the table is heavily loaded the legs will bend more towards the head motion end than if the table were lightly 75 loaded. The result is that when the table is overloaded the stroke becomes longer because of the greater degree of bending of the legs towards the head motion end, and consequently the load is worked off faster. 80 Similarly, when the table has no load, or a lighter load, the vertical inclination of the legs is less and consequently the stroke of arcuate movement of the table is shorter. 85 Consequently with the arrangement above 85 described the stroke of the table, that is, the extent of its arcuate movement, is automatically controlled by the load of ores to be treated the table is called upon to handle.

In practice, and in order to secure the best 90 results, I prefer to key the legs fast at their ends to their respective stringer blocks 19, 28, and precaution should be taken by means of clamps or otherwise as indicated at 49 (see Figs. 2 and 12) to prevent the keys 95 from working loose. Reciprocations are imparted to the table by means of an unbalanced pulley 50 (see Figs. 1, 13 and 14), mounted to revolve upon shaft 30, the latter, as above explained, being mounted in the 100 shaking frame and moving with it. A balanced pulley 51 is also mounted to revolve upon the shaft 30. When the power transmission belt is applied to the balanced pulley 51 no motion is imparted to the shaking 105 frame and table. When, however, the transmission belt is shifted to the unbalanced pulley the shaking frame and table carried thereby receive their vibratory, arcuate or 110 circular arc movement. In practice I prefer to employ an excess of counterweight in the unbalanced pulley over the amount required to handle the usual or average load of ores on the table, so that should an overload occur at any time surplus of power is available 115 to handle the same properly. In practice the unbalanced effect and counterweight of the pulley 50 is attained by bolting on to said pulley auxiliary blocks or pieces as indicated at 52 (Figs. 13 and 14).

120 The action of the unbalanced pulley or counterweight is counteracted by means of a compression coil spring. This counteracting spring may be applied in various positions and relations. In practice, however, and as 125 130

shown, I prefer to place this counterbalancing spring 53 at the head motion end of the structure and to interpose the same between the shaking frame and the floor frame or 5 other suitable fixed part. As shown, the spring 53 is interposed between the cross girt 26 at the head motion end of the shaking frame and the upper end of the arm or lever 23, which, as above described, is hinged 10 or pivoted to the floor frame. The tension of this counteracting spring may be adjusted in any desired manner. In the particular form shown such adjustment is secured by means of the adjusting rod 24 which is connected to the upper end of the pivoted arm 23 and to the corbel 21.

The counteracting spring wherever mounted should preferably be disposed in such manner as to exert its tension at its point of 20 application in a direction with the line of motion of the shaking frame at such point of connection. The function of the spring tension in addition to counteracting the action of the unbalanced pulley is to secure 25 steadiness of the motion imparted to the shaking frame and the table carried thereby and also to prevent undue bending of the flexible supporting legs 39 due to their inclination in a vertical plane towards the 30 head motion end of the table.

The differential or bumping action is secured by means of a pad 54 carried by the girt 26 at the head motion end of the shaking table striking the end of the bumping 35 brace 20. By thus substantially arresting the motion of the shaking frame and table in their movement towards the concentrates discharge end of the table the particles of concentrates or values advance very rapidly 40 over the table surface and towards the concentrates discharge end, and the operation is rendered practically noiseless by suitably constructing the pad 54. I have found that a piece of felt clamped between the pieces 45 of belting well answers the purpose.

It is obvious, of course, that the construction above described permits a variable number of pieces of felt and belting to be employed for the bumper pad 54.

50 The deck or table frame consists, as above explained, of cross beams 37 which in practice I prefer to place in comparatively close proximity as to each other and suitably jointed to the side pieces 55. Upon these 55 cross beams the deck boarding forming the table surface 38 are carried, the deck boarding preferably extending in practice in the direction of the line of motion imparted to the table, thereby securing the maximum 60 degree of bracing effect. The deck of the table is preferably and as usual covered with linoleum. As above explained, the cross beams 37, or certain of them, are hinged at the tailings discharge edge of the 65 table to the hinge brackets 36 carried by the

shaking frame, while at their other ends the deck beams 37 are supported upon the adjusting wedge or inclined surfaces 35 of the adjusting bar through which the angle of transverse inclination of the table may be 70 adjusted. By providing an adjusting wedge or inclined surface 35 for each table deck cross beam 37 warping of the table deck is prevented. A bracket 56 attached to the head motion end of the table at the feed 75 side thereof slidingly receives a bracket or arm 57 carried by the shaking frame. By this construction the feed side of the table is efficiently held to the shaking frame so as to partake of the reciprocatory movements thereof while at the same time permitted to be elevated or depressed through the action of the adjusting wedge bar to vary the transverse inclination of the table. The table surface is provided with riffles 58 80 as in standard practice. Preferably the riffles 58 are of hard wood, and, according to common practice in the art they may be of equal height at the head motion end of the table and for an appreciable distance 85 from said end, after which they taper towards their opposite ends and terminate in a diagonal line, leaving an unriffled portion of the table surface of generally triangular shape at the concentrates discharge end of 90 the table.

I have found in practice that the arrangement of riffles should vary somewhat according to the size of the material handled thereon. In the case of very coarse large 100 sized materials the riffles should extend practically in line with the direction of motion imparted to the table. With medium sized material the riffling should be somewhat out of line with the direction of movement of the table surface, and with finer material and for "slimes" the riffling should be still less in the direction of the motion and since the direction of motion imparted to the table is in the curve of an arc it will 105 of course be understood that when I compare the riffling with reference to the direction of motion imparted to the table I mean that the riffles should be more or less curved in the direction of their length, but 110 of slightly decreasing height above the table surface towards the concentrates discharge end of the table, the curvature of the riffles departing from the curvature of the arc motion of the table according to the size of 115 the material being handled, the curvature being greatest for the coarser sizes of ore.

By thus curving the riffles in the direction of their length and in the general direction of the circular arc motion imparted to the table and more or less in parallel relation to such direction of circular arc motion it will be seen that at their concentrates discharge ends the riffles are disposed "up hill," so to speak, by reason of the transverse inclina- 120 125 130

tion of the table. It will also be seen from the construction above described that the longitudinal inclination of the table as heretofore ordinarily required is dispensed with, 5 the table though transversely inclined remaining level, that is, the tailings discharge edge of the table as well as the feed and wash water edge remaining in horizontal planes although moving in the circular arc 10 path as above described. The riffles, however, being curved more or less towards the concentrates discharge end and towards the higher or feed and wash water side of the table have their concentrates discharge ends 15 disposed somewhat transversely of the table surface and hence may be said to extend "up hill" as the table is transversely inclined. The result is that with this arrangement of riffles combined with the arc movements 20 imparted to the table the concentrates are forced away from the upper sides of the riffles and towards the lower sides of adjacent riffles as indicated at 60 in Figs. 8 and 15 while the gangue or tailings indicated at 25 61 wash over the upper edges of the riffles. Since the tailings discharge side or edge of the table is horizontally level and the riffles run uphill somewhat transversely across the table surface and toward the feed side and 30 concentrates discharge end, the flow of the wash water is more or less in a direction opposite to the direction of travel of the gangue, or material under treatment. This action permits of an unimpeded progress of the 35 concentrates towards the concentrates end of the table, and at the same time increases the rapidity of travel of the concentrates towards the concentrates end of the machine, whereas in prior concentrating tables the 40 progress of the concentrates is more or less impeded and the travel thereof is less rapid. Moreover, the combined action of the riffle arrangement and circular arc motion imparted to the table quickly produces a very 45 thin bed of material on the table surface, thereby permitting a more perfect separation.

As usual in ore concentrating tables the material to be treated is fed onto the table surface from the feed box 62 which is disposed along the upper edge of the table from 50 the head motion end thereof. The wash water is supplied from the box 63 which likewise is disposed along the upper edge of the table and extends from the termination of 55 the feed box to the concentrates discharge end of the table. The concentrates are disposed over the concentrates end of the table into the concentrates receiving box 64.

Referring to the diagram, Fig. 7, and from 60 the foregoing description, it will be understood that in the area A, B, C, D, the tailings have practically no progression toward the concentrates discharge end of the table. The circular arc motion imparted to the 65 table tends to move the tailings in this area toward the concentrates discharge end of the table, but the flow of wash water in the opposite direction restrains the tailings from progressive movement endwise of the table thereby permitting the tailings to be washed 70 over the riffles in a direction transverse to the length of the table. Since the motion of the table is in a circular arc direction, and by reason of the more or less inclined relation of the curved riffles with reference to 75 the direction of the arc movements imparted to the table, the table surface moves rather more uphill and in a direction away from the riffles. The result is the concentrates are thrown more towards the lower sides of the 80 riffles as above explained, where the water accumulation is less, and consequently are carried out upon the relatively smoother un-riffled triangular portion D, C, G, of the table surface without being washed over the 85 riffles along with the tailings. The bulk of the concentrates are delivered over the concentrates discharge end of the table, or that portion thereof extending from G to H, and but very little of the concentrates are discharged over the portion of the concentrates discharge end of the table from H to C. The bulk of the tailings are discharged from the tailings discharge edge of the table from 90 F to B and very little of the tailings are discharged at that portion of the tailings discharge edge from B to C. In fact, in the area J, B, C, K, there is very little of either 95 concentrates or tailings since the separation of the bulk of the concentrates takes place nearer to the upper edge of the table, only a very small part of the tailings being progressed beyond the riffled area from D to K, and this portion of tailings moves of course 100 under the influence of wash water in the 105 direction K, B.

In prior structures of concentrating tables readjustment of the inclination of the table is necessitated in case of any sudden overfeed or underfeed of material to the table 110 surface. This is particularly true in the case of sudden overfeed of material, which event is in practice of rather frequent happening. In such case in the tables heretofore employed the transverse inclination of the 115 table is decreased in order to prevent the concentrates from delivering into the middlings or being carried into the tailings. In case of an overfeed of material with the table above described readjustment of the inclination is not required. The concentrates are efficiently separated and simply are delivered higher up on the table surface without any disturbance of the transverse inclination of the table. Should a condition of 120 overfeed be prolonged, then with the table above described a greater degree of inclination can be given the table surface (instead of decreasing the transverse inclination thereof as heretofore has been found necessary), 125 130

and thereupon an even better separation of concentrates will take place and at a portion of the table higher up than when the table is less inclined, because the tailings fed thins 5 out quickly and the concentrates force ahead unimpeded by riffles or sand.

From the foregoing description it will be seen that I provide an extremely simple structure of table and an extremely simple 10 means for imparting a circular arc motion thereto through a differential motion applied to the same, which circular arc motion while substantially parallel to the discharge side of the table at the head motion end becomes more and more angular in an uphill 15 direction from the discharge side of the table progressively towards the concentrates end of the table, the riffles being similarly disposed, that is, extending in the general 20 direction of the motion, but curved into more or less inclined relation with respect to the motion towards the concentrates discharge ends of the riffles.

It will be also seen that by arranging the 25 flat flexible supporting legs with the planes of their flat faces so inclined relatively to each other as to intersect in the plane of the axis of the unbalanced pulley I am enabled to secure the peculiar circular arc motion 30 which forms an important feature of utility and effectiveness in the operation of the table.

It will also be seen that I provide a table 35 of the bumping or percussion type where the material travels away from the point where the bump is taken, wherein a spring counteracts the surplus or excess of power of the revolving unbalanced pulley, and wherein the spring acts to accelerate the 40 bump, that is, the forward stroke of the table, but opposes the back stroke.

It will also be seen that I provide a table 45 of the character referred to which automatically varies its stroke to accommodate variations in load of material supplied thereto.

While I have shown and described a specific structure of table embodying the principles of my invention, I wish it to be 50 understood that variations therefrom in the details thereof might readily occur to persons skilled in the art and still fall within the spirit and scope of my invention. I do not desire therefore to be limited or restricted to the exact details shown and described.

Having now set forth the object and nature of my invention, and a structure embodying the principles thereof, what I claim 60 as new and useful and of my own invention and desire to secure by Letters Patent of the United States is:—

1. In an ore concentrator, the combination 65 of a table and means for imparting a circular arc motion thereto, the center of the arc

described by said table being at one side thereof, but in the vertical plane of the head motion end of said table, and which plane is at right angles to said end.

2. In an ore concentrator, the combination 70 of a table, of means for imparting vibratory movements longitudinally thereof at the head end, and means for deflecting said movements transversely towards the tail end thereof on an arc of a circle. 75

3. In an ore concentrator, the combination of a table and means for imparting vibratory movements to the same, said movements being initiated in the direction of the length of the table and progressively deflected 80 transversely thereof towards the discharge end of the table, and means for causing a sudden stop of said movements.

4. In an ore concentrator, a transversely inclined table, means for imparting vibratory circular arc movements thereto in the direction of the length of the table, the center of the arc described by said table being at one side thereof but in the vertical plane of the head motion end of said table, 85 and which plane is at right angles thereto.

5. The combination, in an ore concentrator, of a table and riffles thereon, of means for imparting circular arc motion to one end of said table while the other end reciprocates longitudinally, thereby causing ore to separate and discharge the waste tangentially of said riffles. 95

6. The combination in an ore concentrator of a table and curved riffles thereon, of means for imparting vibratory movements to said table, said movements being initiated longitudinally of said table at the head end thereof, and progressively deflected transversely towards the discharge end of said 100 table, thereby discharging ore waste tangentially of said riffles. 105

7. The combination in an ore concentrator, of a table and means for imparting vibratory arc motion to said table at one 110 thereof only, but in the general direction of the length of said table, riffles on said table, said riffles being curved and extending longitudinally along the table whereby, when said table is in motion, ore waste is discharged tangentially of said riffles. 115

8. The combination in an ore concentrator, of a table, and means for imparting vibratory arc motion to said table in the general direction of the length of said table, 120 said motion partaking the path of the arc of a circle at one end of said table, while retaining a longitudinally reciprocable movement at the other end thereof, riffles on said table, said riffles being curved and extending longitudinally along the table, whereby, when said table is in motion, ore waste is discharged at angles to said riffles, said angles increasing near the discharge end of the table. 125 130

9. In an ore concentrator, a table, means for vibrating said table, the initiative vibratory movements being in a direction parallel with the length of the table at the head end, 5 and deflected on a progressively increasing arc towards the opposite end of the table, and means on the surface of said table extending in a direction with the deflected movements, for separating ore particles.
10. 10. In an ore separator and concentrator for separating and concentrating ores, means for initiating rectilinear movements to said ores, means for separating said ores, and means for deflecting one end of said concentrator on an arc of a circle.
11. In an ore concentrator, a vibratory table and supporting legs therefor, said legs being transversely flexible, the axes of flexibility of said legs being disposed at progressively increasing angles to the length of the table.
12. In an ore concentrator, a vibratory table and supporting legs therefor, said legs being transversely flexible, the axes of flexibility of said legs intersecting in a common point removed laterally from the table.
13. In an ore concentrator, a vibratory table and supporting legs therefor, said legs being transversely flexible, the axes of flexibility of said legs intersecting in a common point located at right angles to one end of the table and removed laterally therefrom.
14. In an ore concentrator, a vibratory table, and flat transversely flexible supporting legs therefor, the planes of said legs disposed at progressively increasing angles to the length of the table.
15. In an ore concentrator, a shaking frame, a table carried thereby, a shaft 40 mounted transversely in said frame, an unbalanced pulley mounted to rotate on said shaft, and transversely flexible legs to support said frame, the axes of flexibility of said legs intersecting the axis of said shaft in a common point.
16. In an ore concentrator, a shaking frame having longitudinal side stringers, a girt connecting said stringers at the head end of said stringers, a shaft having its ends carried by said stringers, an unbalanced pulley 50 mounted to rotate on said shaft, a spring acting against one side of said girt, a stationary bumping brace arranged opposite the other side of said girt, and a table carried by said frame.
17. In an ore concentrator, a shaking frame, a table on said frame, an unbalanced rotary pulley carried by the frame to vibrate the same, a bumping brace to arrest the vibratory movement of the table in one direction, a counteracting spring to oppose the vibratory movement of the table in the other direction, and flexible supports for the frame and table.
18. In an ore concentrator, a shaking frame, an unbalanced rotary pulley carried by the frame to vibrate the same, a bumping brace to arrest the vibratory movement of the table in one direction, a spring to oppose the vibratory movement of the table in the other direction, means to adjust the tension of said spring, and a table carried by said frame.
19. In an ore concentrator, a shaking frame carried by flexible supports, an unbalanced rotary pulley carried by said frame, a stationary bumping brace to arrest the frame in one direction of its movement, a spring arranged to exert its tension to oppose the same in the other direction of its movement, a cushion pad to receive the impact of said brace and a table carried by said frame.
20. In an ore concentrator, a vibratory table, and means to automatically vary the period and the course of vibration thereof proportionally to the load imposed thereon.
21. In an ore concentrator, a table, flexible supporting legs therefor, and means connected to said table to vibrate said table on said legs, said legs being vertically inclined to an increasingly greater degree from head to end of the table to thereby vary the length of vibratory stroke of the table proportionally to the weight of the load imposed thereon.
22. In an ore concentrator, a shaking frame, an unbalanced rotary pulley carried thereby, the axis of said pulley extending transversely of said frame, transversely flexible supporting legs for said frame, said legs having their bending axes disposed angularly to the axis of said pulley, and a table carried by said frame.
23. In an ore concentrator, a shaking frame, an unbalanced rotary pulley carried thereby, the axis of said pulley extending transversely of said frame, transversely flexible supporting legs for said frame, said legs having their bending axes disposed angularly to the axis of said pulley, a table carried by said frame, and means to vary the transverse inclination of said table.
24. In an ore concentrator, a shaking frame, an unbalanced rotary pulley carried thereby, the axis of said pulley extending transversely of said frame, transversely flexible legs having their bending axes disposed angularly to the axis of said pulley, a stationary bumping brace to arrest the forward movement of the frame, a spring to accelerate the forward movement of the frame and opposing the rearward movement thereof, and a table carried by said frame.
25. A concentrating table having a deck and a plurality of pairs of vertically extending supports for the deck, each of said supports being fixed from movement at one end and operatively connected to the deck at the opposite end yielding in vertical planes, and

each pair of supports yielding in a different angular direction with relation to the vertical axial plane of the deck, and means for reciprocating the deck.

5 26. A concentrating table including a base frame, a deck, a plurality of pairs of support clamps carried upon the base frame, a plurality of pairs of corresponding support clamps carried upon the deck, the successive

10 sets of clamps being arranged at an increase in angle to the vertical axial plane of the table from the head end to the discharge end thereof, and a plurality of pairs of longitudinally yielding supports mounted in said 15 clamps and supporting the deck.

27. A concentrating table having a deck and a plurality of pairs of vertically extending supports for the deck, said supports being flexible to permit the same to yield in vertical planes, and each pair of supports being arranged at an increase in angle to the vertical axial plane of the table from the head end to the discharge end thereof, and means for reciprocating the deck.

28. A concentrating table including a base frame, a deck, a plurality of pairs of support clamps carried upon the base frame, a plurality of pairs of corresponding support clamps carried upon the deck, and a plurality

30 of pairs of longitudinally yielding supports mounted in said clamps and supporting the deck, the pairs of yielding supports being arranged at an increase in angle to the vertical axial plane of the table from the head

35 end to the discharge end thereof, and means for reciprocating the deck.

29. A concentrating table having a deck, a plurality of pairs of supports for the deck arranged at spaced intervals from the head

40 to the discharge end thereof, each of said supports yielding in a direction approximately parallel to the lengths of the deck, each pair of supports being arranged at a different angular relation to the axis of the

45 deck from any other pair of supports.

30. A concentrating table including a reciprocating deck, a plurality of pairs of supports for the deck arranged at spaced intervals from the head to the discharge end of

50 the deck, each of said supports yielding in a direction approximately parallel to the length of the deck, the supports at the head end yielding in the direction of the deck, and the successive supports toward the tail end

55 of the deck being so arranged that each pair of supports yields in a direction at a greater angle to the length of the deck than the preceding pair of supports, whereby to secure a gradually increasing lateral movement of

60 the deck as the deck is reciprocated.

31. A concentrating table including a reciprocating deck, a base frame, and a plu-

rality of pairs of resilient deck supports rigidly connected at their lower ends to the base frame and at their upper ends to the 65 deck, said supports yielding in a longitudinal direction, each pair of supports being disposed in divergent relation to the vertical, longitudinal, axial plane of the table and at a greater angle to the axis of the table than 70 the pair immediately preceding.

32. A concentrating table including a deck, and a plurality of longitudinally yielding supports fixed at their lower ends and to engage with the deck at their upper ends, 75 certain of said supports being disposed to yield in a direction parallel to the axis of the deck, the supports at the tail end of the table being disposed to yield at an angle to the longitudinal axis thereof, whereby to 80 give a lateral component to the movement of the table at its discharge end.

33. The combination with an element mounted for longitudinal movement, of a shaft, an unbalanced power driven wheel 85 mounted thereon, means for supporting the shaft for movement parallel to the movement of the element, rods operatively connecting the shaft to the element and transmitting motion thereto, a bumper block carried upon said rods, a fixed bumper with which the bumper block engages when the bumper moves forward, and a spring cushioning the rearward movement of the element.

34. The combination with an element mounted for longitudinal movement, of a shaft, an unbalanced power driven wheel mounted thereon, means for supporting the shaft for movement parallel to the movement of the element, rods operatively connecting the shaft to the element and transmitting motion thereto, a bumper block carried upon said rods, a fixed bumper with which the bumper block engages when the bumper moves forward, a spring cushioning the rearward movement of the element, and means for adjusting the tension of said spring.

35. A head motion of the character described including a shaft, a power driven unbalanced wheel mounted upon the shaft, a bumper block operatively connected to the unbalanced wheel to reciprocate therewith and operatively connected to the element to 110 be reciprocated, a fixed bumper disposed in the path of movement of said block, and means for supporting layers of cushioning material upon the face of the bumper block, said means permitting a variable number of 115 layers to be used.

In testimony whereof I have hereunto set my hand on this 8th day of July, A. D. 1918.

GUSTAVE A. OVERSTROM.
